SYDNEY J. SANFORD, OF LOS ANGELES, CALIFORNIA.

MARINE-ENGINE GOVERNOR OR CONTROLLER.

1,366,595.

Specification of Letters Patent. Patented Jan. 25, 1921.

Application filed January 19, 1918. Serial No. 212,795.

To all whom it may concern:

Be it known that I, SYDNEY J. SANFORD, a citizen of Canada, and a resident of Los Angeles, in the county of Los Angeles, State 5 of California, United States of America, have invented certain new and useful Marine-Engine Governors or Controllers, of which the following is a specification.

Objects of the present invention are to 10 provide simple, reliable and efficient means for preventing the propeller from racing when it comes out of the water in a heavy sea and to control the engine from the bridge in such manner that an officer in charge in 15 an emergency can handle it by the movement of a switch which will automatically slow up, stop or reverse without the intervention of the engineer.

The invention will be claimed at the end 20 hereof, but will be first described in connection with the embodiment of it chosen for illustration in the accompanying drawings, in which—

Figure 1, is a view, partly in section and 25 partly in elevation, of mechanism embodying features of the invention,

Fig. 2, is a diagrammatic view, partly in section, illustrating a modification of one of 30 the parts and also illustrating diagrammatically the circuit connections.

Fig. 3, is a sectional view drawn to an enlarged scale and taken through the fixed and bridge contacts, and

Fig. 4, is a plan view also drawn to an enlarged scale, of a portion of the bridge element.

In the drawings 1, is a source of current and there is an advantage in the use of alternating current as will appear from the following description in connection with certain plates between which current passes through the sea water and which, if direct current were employed, would be subject to electrolysis. There is a solenoid 2, the core-

45 bar 3 of which is adapted to control the engine gear. The type of engine controlled by the core-bar 3 is not important, but in the drawings I have illustrated parts of a reciprocating engine controlled by a link 50 valve-gear 4, through the intervention of a pilot engine 5, the valve of which is operated from the core-bar 3 by a bell-crank 6 and link 7, and from this illustration those skilled in the art will understand that from the 55 core-bar 3 the control gear of a turbine or

of an electric transmission connected therewith can be effected without requiring further illustration or description.

The solenoid 2 is provided with windings, each connected to one pole of the source as 60 by the conductor 8, provided with branches to each of them, and these windings are arranged in opposed pairs which are marked a, a^1, b, b^1, c, c^1 and d, d^1 , the intermediate winding being marked e . There are switch 65 contacts in forward and reverse sets; those in one set, for example the forward or ahead set, are marked a^2, b^2, c^2 and d^2 and those in the reverse set are marked a^3, b^3, c^3 and d^3 . The same letters are used because of the 70 relation between these contacts and the windings of corresponding letter. Connections from the other pole of the source 1 extend to a switch contact in each set and from thence to the windings of opposed pairs of windings. The connection a^4 by branches a^5 and a^{61} extends to one of the separated conductors constituting the switch contacts a^2 and a^3 and from the other of the separated conductors by conductors a^6 and a^7 to 75 the windings a, a^1 . The connection b^4 by branches b^5 and b^{61} extend to one of the separated conductors constituting the switch contacts b^2 and b^3 and from the other of the separated conductors by 80 conductors b^6 and b^7 to the windings b, b^1 . The connection c^4 by branches c^5 and c^{61} extend to one of the separated conductors constituting the switch contacts c^2 and c^3 and from the other of the separated conductors by 85 conductors c^6 and c^7 to the windings c, c^1 . The connection d^4 by branches d^5 and d^{61} , extend to one of the separated conductors constituting the switch contacts d^2 and d^3 and from the other of the separated conductors by conductors d^6 and d^7 to the windings d, d^1 . The winding e is connected by a conductor 9 through a rheostat 10 to one pole of the source 1.

There are means by which the connections 100 a^4, b^4, c^4 and d^4 are appropriately connected in the circuit. An example of these means are plates or electrodes A, B, C, D and P, of which one P, is connected to one pole of the source 1, and which are arranged at different levels near the propeller and adapted for emersion and submersion in the sea water to complete the circuit. When they are all submerged the circuit is as has been described, but when some of them are emerged 105 110

they are no longer in the circuit nor are the windings to which they are connected. 11, is a bridge element having, as shown, three main positions and it is operated by a handle, 5 accessible from the bridge.

In the following description of the mode of operation it will be assumed that the plates or electrodes A, B, C, D, and P are present and that both functions of the invention are available. However, it may be remarked that in the case of the equipment of a vessel already in service the installation of the plates may be postponed until a convenient time, in which time they are replaced by a solid conductor, and in the mean time the advantage of the function of the control of the engine from the bridge will be attained but not that of automatic prevention of engine racing. Of course the 10 various wires or conductors making up the circuit connections may be arranged in the form of a cable and passed through the wall of the ship at one convenient place, as 13 in Fig. 1, and in Fig. 2, the solenoid is in effect made double and is provided with two cores 3 and 3^a connected together and the windings are merely duplicated and hence it is unnecessary to cloud the drawing by 15 additionally lettering the duplicate windings.

Since the winding e is always in circuit it tends to retract and centralize the core-bars and it also keeps them constantly energized, which is obviously a matter of advantage in some cases, because the cores being constantly magnetized will respond more quickly to the pull of the magnetization of an additional coil or coils than they would do if they were not constantly energized, 20 and the rheostat serves to adjust the branch containing the winding e in respect to the resistance of the water in its effect upon the passage of current between the plates A, B, C, D, and P. When all of these plates are submerged and all of the circuits are broken at the switch contacts, for example, by positioning the bridge element 11 intermediate of them, the core-bars are in central or neutral position under the influence of the winding e and in this position the engine control-gear is positioned to stop the propeller. If the officer in charge of the bridge shifts the bridge element 11 counter-clockwise from intermediate position the result 25 is to bridge the contacts d², c², b² and a², thus bringing into circuit the windings to which these contacts are connected, one after another, thus shifting the effective field of the solenoid and causing the core-bars to move toward the left in the drawing, which movement is assumed to produce progressive ahead motion of the propeller. A return of the bridge element to its middle position 30 similarly cuts out these windings suc-

sively and so shifts the field of the solenoid 65 producing movement of the core-bar which operates on the engine control gear to slow down and finally stop the propeller, which it does when the bridge element is in middle position. Movement of the bridge element 70 toward the right similarly operates upon the windings a¹, b¹, c¹ and d¹, shifting the field of the solenoid and bringing about the same control of the propeller but in the reverse direction. No matter what the position of the bridge element may be so long as it is bridging contacts, if the plates or some of them D, C, B, A, emerge from the water, those windings which are connected to them are cut out of the circuit thus causing shifting of the solenoid field appropriate for working the engine control gear to prevent the propeller from racing.

To operate in the manner described, the bridge element 11, is provided with a series 85 of bridge strips or contacts 11^a, insulated from it and from each other and adapted to span the contacts in pairs.

It will be obvious to those skilled in the art to which the invention relates that modifications may be made in details of construction and arrangement without departing from the spirit of the invention, which is not limited as to those matters or otherwise than as the prior state of the art and the appended claims may require.

What I claim is:

1. A marine engine governor and controller comprising the combination of a source of alternating current electrolytically inert, a solenoid core-bar adapted to actuate the marine engine control gear, a plurality of windings for said bar connected to one pole of the source and of which some are mate opposed windings and of which one is 105 an intermediate winding and is always in circuit to centralize the bar and stop the engine, a stop and ahead and reverse three-position switch having multiple mate-contacts for forward and reverse, a circuit connection from one pole of the source through mate-switch contacts to individual mate-coils, and spaced plates adapted for successive emergence and submersion and of which some are connected to mate-switch contacts 110 and of which one is connected to the source to oppose engine racing.

2. In apparatus of the class described the combination of a source of current, a solenoid core-bar adapted to actuate the marine engine control gear, a plurality of windings for said bar connected to one pole of the source and of which some are mate opposed windings and of which one is an intermediate winding and is always in circuit to 125 centralize the bar and stop the engine, a stop and ahead and reverse three-position switch having multiple mate-contacts for

forward and reverse, and circuit connections from the last mentioned contacts to the opposed mate-windings.

3. A marine engine governor and controller comprising the combination of a source of current, a solenoid having windings each connected to one pole of the source and arranged in opposed pairs and adapted to control the engine gear, switch contacts in forward and reverse sets, connections from the other pole of the source to a switch contact in each set and from thence to the windings of opposed pairs of windings, a bridge element for the switch contacts and spaced plates adapted for successive emergence and submersion of which some are connected with a switch contact in each set and of which one is connected to the source.
4. A marine engine governor and controller comprising the combination of a source of current, a solenoid having a normally retracted core-bar and having an intermediate winding and other windings each connected to one pole of the source and arranged in opposed pairs and adapted to control the engine gear, connections including a rheostat for permanently energizing the intermediate winding of the solenoid, switch contacts in forward and reverse sets, connections from the other pole of the source to a switch contact in each set and from thence to the windings of opposed pairs of windings, and a bridge element for the switch contacts.

to the windings of opposed pairs of windings, a bridge element for the switch contacts, and spaced plates of which some are connected with a switch contact in each set and of which one is connected to the source.

5. In apparatus of the class described the combination of a source of current, a solenoid having a normally retracted core-bar and having windings each connected to one pole of the source and arranged in opposed pairs and adapted to control the engine gear, connections including a rheostat for permanently energizing an intermediate winding of the solenoid, switch contacts in forward and reverse sets, connections from the other pole of the source to a switch contact in each set and from thence to the windings of opposed pairs of windings, and a bridge element for the switch contacts.

6. In apparatus of the class described the combination of a source of current, a solenoid having windings each connected to one pole of the source and arranged in opposed pairs and adapted to control the engine gear, and electrodes spaced at different levels for successive submersion and emergence and of which some are connected to the same pole of the source in series relation to the windings and of which one is connected to the other pole of the source.

SYDNEY J. SANFORD.
